DESIGN FOR A COMBINED LUGGAGE CARRIER AND CONTAINER FOR A BICYCLE OR THE LIKE

John R. Morgan, Oak Park, Ill., assignor to Sears, Roebuck and Co., Chicago, Ill., a corporation of New York

Application November 10, 1938, Serial No. 81,011

Term of patent 7 years

To all whom it may concern:

Be it known that I, John R. Morgan, a citizen of the Republic of Guatemala, residing in Oak Park, in the county of Cook and State of Illinois, have invented a new, original, and ornamental Design for a Combined Luggage Carrier and Container for a Bicycle or the like, of which the following is a specification, reference being had to the accompanying drawing, forming a part thereof.

Fig. 1 is a top plan view of a combined luggage

carrier and container for a bicycle or the like embodying my new design.

Fig. 2 is a side elevational view of the same.

Fig. 3 is a front elevational view thereof.

Fig. 4 is a rear elevational view of the carrier element.

I claim:

The ornamental design for a combined luggage carrier and container for a bicycle or the like, as shown.

JOHN R. MORGAN.
